UNITED STATES PATENT OFFICE.

CARL ERIC ANDERSON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

1,385,296.

Specification of Letters Patent. Patented July 19, 1921.

Application filed October 23, 1916. Serial No. 127,146.

To all whom it may concern:

Be it known that I, CARL ERIC ANDERSON, a citizen of the United States of America, and residing at Bridgeport, in the county 5 of Fairfield and State of Connecticut, have invented a certain new and Improved Electric Switch, of which the following is a specification.

My invention relates to electric switches 10 and particularly to switches of the flush type generally used for controlling lighting or other local circuits. The object of my invention is to provide a simplified and improved mechanism which is efficient and 15 serviceable in operation.

Referring to the accompanying drawings,

Figure 1 is a plan, partially in section, of a switch in which my invention is embodied in one form;

20 Fig. 2 is a longitudinal section therethrough on the lines 2—2, Fig. 1;

Fig. 3 is a detached perspective of the several switch elements; and

25 Fig. 4 is a perspective of one of the combined wire and switch terminals.

The switch in the form here shown comprises a cup-shaped insulating body 10 having a yoke 11 which extends longitudinally across the open face of the body and is held 30 in position by screw bolts 12, and by which the switch may be mounted in any suitable outlet box (not shown). A cover plate 13 of ordinary type is secured to the yoke by screws 14. The corners of the body 10 are depressed to afford apertures 15 through which connecting wires may be led to the wire terminals 16. The latter are secured by screws 17 passing through the bottom of the cup and taking into tapped holes in the foot 40 piece 18 of each terminal. Switch contacts 19 extend into the switch chamber 20 from the wire terminals 16 and coöperate with the switch blades 21. In the present construction the switch is shown as of the double-pole type, although obviously by omitting one of the switch blades and the corresponding wire terminals and switch contacts it becomes a single pole switch, the mechanism of which is otherwise the same.

50 Extending into the switch chamber are ribs 22 at each end of the insulating body 10, channeled at 23 for the major portion of their depth to form ledges which receive the securing lugs 24 of the switch frame 25.

The base of the latter lies against the bottom of the switch chamber, while upstanding lugs 26 form standards on opposite sides of the base of the frame and serve to support the switch mechanism. The switch mechanism proper comprises a pair of push buttons 27, the shanks of which are angled toward each other at their inner ends and provided with lugs 29 adapted to engage in holes 30 on opposite sides of the axis 31 of a rocking member which comprises a pair of 60 similarly shaped plates 32. The latter are mounted between the standards 26 on the pivot pin 33 which passes through the holes 34 in the standards and the holes 31 in the plates 32. The shanks 28 of the push 65 buttons 27 form spacers between the plates 32 and are of such width that the plates 32 are held close to the standards 26. There is consequently no danger of the lugs 29 escaping the holes 30 after the rocker plates 70 32 have been assembled with the push buttons and frame and mounted upon their pivot pin 33.

Each plate 32 has a lug 35 extending outward from a point midway between the arms 80 to which the push buttons are attached and pierced at 36 to receive a cross pin 37 which serves as an abutment for the switch spring 38. The latter is coiled upon a guide pin 39 comprising a pair of straps of like shape spaced adjacent the end 40 to afford a limited freeway for the cross pin 37 and provided at their opposite ends with registering cross arms 41 which form an abutment for the opposite end of the spring 38. The head 42 90 of the cross pin enters the slot 43 in the yoke 44 which carries the switch blades 21. The two straps of the guide pin 39 are held together by the coil spring 38 slipped thereover, and the abutment pin 37 may be inserted transversely after a slight compression of the spring 38 against the cross arm 41.

The switch yoke 44 carries at its open end a pair of oppositely-faced pivot studs 45. 100 In the assembled position of the switch these studs rest in open bearings 46 formed in the outer ends of the standards 26 by offsetting apart the free ends of the latter and carrying the slots 47 which form the open bearings 105 46 through the offsetting shoulder 48. By properly spacing apart the arms of the yoke 44 with relation to the standards 26, it is

possible to assemble the yoke on the frame by merely slipping the studs along the shoulders 48 until they enter the slots 47, after which they are automatically seated in their bearings 46 and maintained therein by the pressure of the switch spring 38. The free ends of the standards 26 are fan-shaped and provided with shoulders 49 which form stops against which the yoke 44 comes to rest in its extreme position. The throw of the rocker plate 32 is limited by the impingement of its push button arms against the bottom of the frame 25.

The operation of the switch is readily understood by referring to Fig. 2. To open the switch, the right hand button 27 is depressed, with the result that the arm 35 of the rocker plate 32 is swung up and past the axis of oscillation of the switch yoke 44, whereupon the pressure of the spring 38 (now further compressed) is exerted in a direction to throw the switch yoke 44 to the left, thus moving the blades 21 out of contact with switch terminals 19. To again close the switch the left hand push button, which is now up, is depressed with a resulting reversal of the action just described.

Various modifications of construction will readily occur to those skilled in the art with-

out departing from what I claim as my invention.

I claim as my invention:—

An electric switch comprising a cup-shaped rectangular body of insulating material having at its opposite ends ribs extending into the switch chamber, depressed ledges formed by channels in said ribs, a switch frame having a base resting against the bottom of the switch chamber and upwardly angled end lugs overlying said ledges and secured thereto, standards rising from the opposite sides of said base and having open bearings formed therein, a rocker pivoted to said standards adjacent the base, a switch piece pivoted in said open bearings in the standards above the axis of the rocker, a switch spring operatively interposed between said rocker and switch piece, and means for actuating said rocker, for the purpose described.

In testimony whereof I have signed my name to this specification, in the presence of two subscribing witnesses.

CARL ERIC ANDERSON.
